UNITED STATES PATENT OFFICE.

THOMAS CALDWELL, OF BOLTON, AND WILLIAM CALDWELL, OF LEIGH, ENGLAND, ASSIGNORS, BY MESNE ASSIGNMENTS, TO THE RADAX PNEUMATIC TYRE COMPANY, LIMITED, OF WARRINGTON, ENGLAND.

LOOM.

SPECIFICATION forming part of Letters Patent No. 651,744, dated June 12, 1900.

Application filed July 18, 1898. Serial No. 686,299. (No model.)

To all whom it may concern:

Be it known that we, THOMAS CALDWELL, cycle agent, residing at 137 Blackburn road, Bolton, and WILLIAM CALDWELL, cotton-mill manager, residing at Vicarage Square, Leigh, in the county of Lancaster, England, subjects of the Queen of Great Britain, have invented a Loom, of which the following is a specification.

This invention relates to the manufacture of textile fabric for forming the outer covers for pneumatic tires or other similarly-shaped articles and apparatus therefor, and has for its object to produce such fabric of a curved form or shape—*i. e.*, curved to a radius and somewhat of an inverted **V** shape or **U** shape in cross-sections—as, for instance, in forming covers for pneumatic tires the fabric is made of (or about) the radius and cross-sectional form which the outer cover will assume when fully inflated on the rim. This object is obtained by differentiating the amount of length of warp in the fabric from the center to the selvage, greater length of warp being put in the center than in the selvages and advantageously in a graduated manner from the center toward each selvage and proportioned according to the shape desired. The weft may be put in either in a regular or irregular manner, as desired. For instance, we may put more weft-picks in the central part of the fabric than in the outer edge, as hereinafter described.

We will now, therefore, proceed to describe our present invention with reference to the accompanying drawings.

Figure 1 is a diagrammatic side view of apparatus according to our present invention which can be applied to any suitable loom—such, for instance, as an ordinary cotton-cloth loom. Fig. 2 is a view taken on the line 2 2 of Fig. 1 and looking in the direction of the arrow 1, Fig. 1. Fig. 3 is a “local” detail view, on an enlarged scale in side elevation, of the attachment or means which we provide according to the present invention to keep the fell of the cloth flat or level for the beat up. Fig. 4 is a plan of Fig. 3. Fig. 5 is a local detail view, in side elevation, showing the means

according to the present invention for drawing or winding off the made fabric. Fig. 5^a is a detail view looking at the edge of the concave roller shown in Fig. 5. Fig. 6 is a vertical sectional view taken on the line 6 6, Fig. 5, and looking in the direction of the arrow 55. Fig. 7 is a local plan view (diagram) of a modified arrangement of the warp-beams or bobbins—viz., the latter are arranged in a horizontal plane instead of in a vertical plane, as shown in Fig. 1. Fig. 8 shows a diagram 60 of the weave.

Similar letters of reference indicate corresponding parts throughout.

In an ordinary or any suitable loom the warp-threads *a* are arranged or mounted in several sections or groups. For instance, the center section *A* is on a beam *X'* of its own. (See Figs. 1 and 2 and diagram Fig. 8.) The section or group *B* of warp on each side of the center group *A* and next adjoining thereto comes off another bobbin or beam *X²*. The succeeding group of warp *C* is arranged so that half the threads go to one side and half to the other side of the warp groups *B* immediately preceding it, and so on through the whole series, the threads *a* being mounted on separate and independent beams or bobbins *X'* *X²*, and so on, or otherwise suitably arranged in suchwise that the various warp-threads or groups of threads *A* *B* *C*, &c., respectively, can be drawn off, as required, independently of one another.

A drum or barrel *b* having varying diameters arranged in a graduated manner—for instance, with the greatest diameter midway of its length and descending (decreasing) step by step toward each end (or a number of separate drums of different diameters may be similarly arranged)—is or may be mounted in such a position that the warp-threads *a* will be led around or partly around same as said threads are drawn off their bobbins or beams in the above-mentioned proportions.

Instead of using the ordinary breast-beam *c* and taking-up rollers (not shown) according to the present invention we arrange and mount on or over said breast-beam a specially-shaped horn or ridge *d* of a curved

form both longitudinally and crosswise, (see Figs. 5 and 6,) such shape corresponding (or thereabout) to the radius and cross-section of the tire for which said outer cover is intended, and we also provide a convex roller or drum *e*, (see Figs. 1, 5, and 6,) the convexity of same advantageously corresponding or thereabout to said ridge, and a small concave roller *f* (which in such case would bear against convex roller *e*) is mounted proximate thereto, or other suitable means may be employed so as to draw off the fabric as produced, said drawing-off rollers *e* and *f* being driven or actuated in any suitable manner, or the drawing-off roller *f* may be mounted a little distance from the roller *e*, as shown in Fig. 5, and we may use a piece of flexible material *g*, somewhat like a band-brake, such as strong canvas, which embraces the aforesaid convex drawing-off wheel or roller for, say, less than half its circumference and against which (with the newly-woven fabric in between) it is very strongly pressed or drawn by means of strong springs *h* and *i*, to which latter said band-brake or device *g* is securely attached at *h'* and *i'*, respectively, the springs *h* at the front being stronger than and adapted to overcome the springs *i* at the other end, said springs *h* and *i* being attached at *j* to a fixed part of the loom, whereby the newly-woven fabric *a^{xx}* is firmly pressed onto the convex drawing-off roller *e*, which latter may be roughened or other than smooth around its circumference.

35 As the employment of the aforesaid horn or ridge *d* (which is fixed or mounted close up to the fell of the cloth) causes the warp threads *a* to lie in different planes, and consequently would cause an uneven shed and 40 would interfere with the traverse of the shuttle. To avoid this and in order to keep the fell off the cloth at *a^{xx}* flat or level we form, arrange, or mount any suitable fixed guiding-bar or guiding device—such, for instance, as 45 a long horizontal slot—in a device fixed or mounted on the frame or other suitable part of the machine advantageously with one or more side or sides forming said slot removable, so that the warp-threads can be readily 50 laid in or removed therefrom when desired, the position of this device being such as to be out of reach of the reed, &c., on the beat up. For instance, the arm *m* is rigidly fixed to the breast-beam *c* and extends toward the 55 reed *n* and is forked or widened at *m'* and carries two upwardly-extending side lugs, cheeks, or bearings *m²* or equivalent in suchwise that a detachable pin or cross-bar *o* can be readily and firmly affixed in position in 60 said supports *m²*, or said pin or cross-bar may be hinged at one end, if desired, so as to hold the fell of the cloth *a^{xx}* level.

A mode of weaving is as follows: The warp-threads *a* are arranged in the healds *p* in such- 65 wise that each section or group of threads may be operated independently or in combination with any or all of the other groups of

threads, so as to permit the weft being introduced and the wearing to be effected as follows: First, the healds *p* are so operated by a dobby (or other suitable mechanism at *q*) that the weft for the first few picks—say four—is shot right across, (see Fig. 8;) but on the return shoot thereof the shed of all the sections on the shuttle side up to the middle section 75 are left open. For instance, with eleven sections the first five are left open, the weft first binding on the outer thread *A'* of the middle section *A* and then passing through to the other side of the loom. Next the shed of the 80 five sections on this other side is left open, and the weft now binds on the other outer thread *A²* of the middle section *A*, and the shuttle continues right across. Next the shed is changed for a complete shoot, thus leaving a six-section pick in. Then several complete shoots—say three—are effected, and then another complete shoot 10, and now on the return shoot the shed is left open for the four outside sections, the weft being now bound on the outer thread *B'* of the fifth section *B* and passes right across similarly for the next pick. The shed on the other side is left open, the weft binding on the outer thread *B²* of the fifth section *B* on this side and passing to the 95 opposite side, when the shed is again altered, leaving a seven-section pick in and then several complete shoots, and so on progressively until all the sections have been thus progressively taken in by the selective picks, whereupon the cycle of operations is repeated, beginning with the middle section, as first described, and so on, as will be readily understood on reference to Fig. 8.

The hereinbefore-described arrangement of 105 independently-mounted warp-threads *a* permits the latter to travel at different speeds, and a greater length of warp goes into the central section *A* than into the next outer sections *B*, and so on successively, the least warp 110 going into the two outside sections forming the outer edges of the fabrics. These outer sections, however, travel slower than the inner sections, and the latter travel slower than the central section. Thus notwithstanding the 115 unequal number of picks inserted in the different parts of the width of the material nevertheless an approximately-uniform fabric or 120 closeness of texture is produced, the extra picks in the central portions going to fill up the extra length of warp, as aforesaid, and the finished fabric is formed or assumes the curved shape desired both in radius and cross-section.

In place of using healds or their equivalents we may use Jacquard harness, in which case each individual warp-thread may be independently operated and drawn off independent bobbins.

What we claim is—

1. In a loom, the combination of means for holding the fell of the fabric flat, a curved drawing-off ridge, a roller with a convex face, a band-brake, between which and the roller

the fabric passes, and means for pressing the band-brake against the fabric or roll, substantially as described.

2. In a loom, the combination of a frame 5 provided with a bar under which the fabric is adapted to pass, a curved drawing-off ridge, a roller with a convex face, a band-brake and means for holding said brake against the roller, substantially as described.

10 3. In a loom, the combination of a curved drawing-off ridge, a roller having a convex face, a band-brake and means for holding said brake against the roller or the fabric thereon, substantially as described.

15 4. In a loom, the combination of a curved drawing-off ridge, a roller with a convex face, a band-brake and differential springs tending to hold said brake in contact with said roller, substantially as described.

20 5. In a loom, the combination of a curved drawing-off ridge, a roller with a convex face, a band-brake, springs tending to hold said brake against said roller, and a concave roller over which the fabric passes after leaving the

25 convex roller, substantially as described.

6. The combination in a weaving-loom of a curved drawing-off ridge or convex surface over which latter the made fabric is drawn in order that the middle portion of the strip

of fabric may have more warp than the outer 30 portions so that said fabric is formed curved in the direction of its length, a correspondingly-convex roller, *e*, and a pressure-band *g* held tightly on the said roller *e* by the opposing springs *h* and *i* with the fabric *a* between said band-brake *g* and the said convex roller *e* substantially as and for the purposes set forth.

7. The combination in a weaving-loom of a curved drawing-off ridge or convex surface 40 over which latter the made fabric is drawn in order that the middle portion of the strip of fabric may have more warp than the outer portions so that said fabric is formed curved in the direction of its length, a correspondingly-convex roller *e*, a pressure-band *g* held tightly on the said roller *e* by the opposing springs *h* and *i* with the fabric *a* between said pressure-band *g* and the said convex roller *e*, and means to hold flat or level the 45 fell of the cloth and the warp-threads at the latter point, substantially as and for the purposes set forth.
